DESIGN FOR A DOILY

Kenneth C. Hamilton, Milwaukee, Wis., assignor to Milwaukee Lace Paper Company, Milwaukee, Wis., a corporation of Wisconsin

Application January 20, 1936, Serial No. 60,698

Term of patent 14 years

To all whom it may concern:

Be it known that I, Kenneth C. Hamilton, a citizen of the United States, residing at Milwaukee, in the county of Milwaukee and State of Wisconsin, have invented a new, original, and ornamental Design for a Doily, of which the following is a specification, reference being had to the accompanying drawing, forming a part thereof.

The single figure of the drawing is a fragmentary face view of a doily embodying my new design, showing approximately three-fourths of the doily in outline. The full lines of the drawing show one-fourth of the design in detail, which design is repeated symmetrically in each of the other three-fourths of the doily.

I claim:

The ornamental design for a doily, substantially as shown and described.

In witness whereof, I hereunto subscribe my name this 7th day of January, 1936.
